(57) **CLAIM**

An ornamental design for a modular sensor platform, as shown.

DESCRIPTION

The invention described herein may be manufactured, used and/or licensed by or for the United States Government.

FIG. 1 is as top plan view of the modular sensor platform showing the first embodiment of our new design;

FIG. 2 is a right side elevational view thereof;

FIG. 3 is a rear elevational view thereof;

FIG. 4 is a right side elevational view thereof with the top cover in the open position;

FIG. 5 is a right side elevational view thereof with whole top housing in the raised position;

FIG. 6 is a front elevational view thereof;

FIG. 7 is a bottom plan view thereof;

FIG. 8 is a top plan view of a second embodiment of our new design of FIGS. 1-7;

FIG. 9 is a top and right-front perspective view thereof;

FIG. 10 is a left side elevational view thereof;

FIG. 11 is a front elevational view thereof;

FIG. 12 is a right side elevational view thereof; and,

FIG. 13 is a rear elevational view thereof.

The broken line showings are for illustrative purposes only and form no part of the claimed design.
